Primary Examiner — Wendy L Arminio*Assistant Examiner* — Maheen Khurshid(74) *Attorney, Agent, or Firm* — Birch, Stewart, Kolasch & Birch, LLP(57) **CLAIM**

The ornamental design for a bellows device, as shown and described.

DESCRIPTION

FIG. 1 is a front view of a bellows device showing my new design;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is a bottom perspective view thereof;

FIG. 8 is another bottom perspective view thereof; and,

FIG. 9 is a right side perspective view thereof.

The broken lines depict portions of the bellows device that form no part of the claimed design.
